UNITED STATES PATENT OFFICE.

MARIE LARSEN, OF JAMAICA, NEW YORK.

WASHDRAINER.

1,243,841.

Specification of Letters Patent. Patented Oct. 23, 1917.

Application filed May 13, 1915. Serial No. 27,814.

To all whom it may concern:

Be it known that I, MARIE LARSEN, a citizen of the United States, residing at Jamaica, in the county of Queens and State of New York, have invented certain new and useful Improvements in Washdrainers, of which the following is a specification.

This invention relates to new and useful improvements in laundry apparatus, and pertains more particularly to devices for draining wet clothes.

The primary object of the invention is to provide a device of this character which is especially adapted for use with a clothes boiler of the ordinary type.

A further object of the invention is to provide a device of this character which can be readily transported when full of clothes.

Referring to the drawings;

Figure 1 is a view in elevation of a clothes boiler with the clothes drainer in position thereon;

Fig. 2 is a sectional view of the drainer;

Fig. 3 is a top plan view of the drainer;

Fig. 4 is a front elevation thereof.

Referring to the drawings by reference character, 1 designates the bottom of the drainer, which is preferably formed of wire mesh, and has a straight forward edge 2, parallel rearwardly extending side walls 3, and a curved rear wall 4 which latter connects the parallel side walls 3.

Extending upwardly from the bottom 1 and conforming to the shape thereof is a vertically extending flange 5, said flange being secured to the bottom 1 by turning up a flange 6 on the edge thereof which is adapted to receive the flange 5 and be secured thereto by rivets or the like not herein shown. The flange 5 is provided with a plurality of openings 7 for the purpose of permitting of water draining therethrough.

Extending downwardly into the interior of the vertical flange 5 is the upper portion 8 of the drainer, said upper portion consisting of an integral outwardly flaring side and rear wall 9 the upper edge of which is rolled over to provide a smooth upper edge 10.

As seen in Fig. 4 the front portion of the vertical flange 5 extends upwardly into engagement with the front edges of the side walls 9 as at 12, and is secured thereto by means of the vertically extending angle irons

11 which are riveted thereto. As will be seen, the front walls of the angle irons 11 terminate at points flush with the top edges of the portions 12 of the flange 5.

The side walls 9 are provided on their outer faces with handles 13 while the vertical flange 5 is provided with right angular brackets 14 which are adapted to engage the upper edge of the boiler 15 and form means for supporting the device. There are three of these right angular brackets arranged one on each side of the flange 5 and one at the rear thereof.

In use the handles are grasped to lift the device, and it is placed inside of the upper portion of a boiler as shown in Fig. 1 with the right angular brackets 14 in engagement with the upper edge of the boiler, clothes which have been previously boiled in the boiler are lifted out of the same, and are placed upon the wire bottom 1 where the water is permitted to drain back into the boiler.

Having thus described my invention what I claim as new, and desire to protect by Letters Patent is:

A wash drainer comprising in combination with a wash boiler, a perforated sheet metal member conforming in shape to the contour of one end of the boiler, a plurality of supporting members secured to the outer face of the perforated sheet metal member and adapted to engage the upper edge of the boiler, a wire mesh bottom for the sheet metal member and secured thereto by crimping the lower edge about a flange carried by the mesh bottom, an outwardly flaring upper section rigidly secured to the upper edge of the perforated sheet metal member, a perforated front wall connecting the ends of the perforated sheet metal member, and having end portions extending above the perforated sheet metal member, and angle bars connected to the perforated sheet metal member, the perforated front wall and the outwardly flaring upper section, said angle bars serving to secure said perforated sheet metal member, said front wall, and said upper section in rigid relation.

In testimony whereof I affix my signature in presence of two witnesses.

MARIE LARSEN.
